UNITED STATES PATENT OFFICE.

FREDERICK W. PARSONS, OF ELMIRA, NEW YORK, ASSIGNOR TO INGERSOLL-RAND COMPANY, OF JERSEY CITY, NEW JERSEY, A CORPORATION OF NEW JERSEY.

COMPRESSOR VALVE.

Application filed January 14, 1922. Serial No. 529,283.

To all whom it may concern:

Be it known that I, FREDERICK W. PARSONS, a citizen of the United States, and a resident of Elmira, county of Chemung, 5 and State of New York, have invented a certain Compressor Valve, of which the following is a specification accompanied by drawings.

This invention relates to compressors, but 10 more particularly to a valve for controlling the inlet and discharge of the cylinder.

One of the objects of the invention is to enable both the inlet and discharge of the compressor to be controlled by means of one 15 mechanically operated valve, which may preferably have several parts, as for instance a main valve member and an auxiliary valve member carried thereby, although the invention is not to be limited to any particular type or construction of valve.

Another object of the invention is to produce a mechanically operated valve capable of being adjusted to vary the point of opening of the discharge for different ratios of 20 compression. By this means, the valve may be manually adjusted for controlling variable pressures so that the discharge opening occurs when the pressure in the cylinder substantially coincides with the pressure 25 in the discharge passage, although such a mechanically operated valve could be constructed to automatically vary the said discharge opening, without departing from the spirit of my invention as defined in this 30 specification and in the appended claims.

In the drawings, in which one preferred embodiment of the invention is shown,

Figure 1 is a top plan view, partly in horizontal section of so much of a compressor and valve and valve gear as will serve 40 to illustrate the invention.

Figure 2 is a side elevation of the parts of the machine shown in Figure 1, partly broken away for simplicity,

Figure 3 is an enlarged detail horizontal sectional view through the cylinder and valve chest shown in Figure 1, with the discharge at the opening point for one adjustment of the valve,

Figure 4 is a view similar to Figure 3, with the valve so adjusted that the point of opening of the discharge will be later in the cycle of operations than in Figure 3.

Figures 5, 6, 7 and 8 are diagrammatic 55 views partly in horizontal section showing

the relative positions of the piston and valve through different parts of the piston stroke. For clearness of illustration the valve actuating cams in these figures are shown as if they were in horizontal planes 60 instead of in their proper vertical planes.

Referring to the drawings, the compressor cylinder A, having the intake B is provided with the reciprocating piston C driven in any suitable manner from the crank D. The 65 cylinder is provided with a valve chest E in which a piston valve reciprocates for controlling both the inlet and discharge of the cylinder.

In this instance, the piston valve comprises the main valve member or piston F having closed ends and the auxiliary valve member, in the form of adjustable slides G and H, which may be moved to and from each other within the main valve member F 70 by suitable mechanism. The discharge takes place from the valve chest through the discharge pipe J and the main valve member F preferably slides within the ported sleeve K.

Any suitable operative devices and mechanism may be provided for mechanically actuating the members of the compressor valve from the main and auxiliary eccentrics L and O on the crank shaft P. In this 75 instance, the main eccentric strap Q is pivotally connected to the yoke S to which the valve rods T and U are connected for actuating the main valve member F. The auxiliary eccentric strap R is pivotally connected 80 to a sliding rod V carrying an arm W, through which the auxiliary valve rod X rotatably extends but is held from longitudinal movement by means of the nuts Y.

The slides G and H forming the auxiliary 85 valve member are threaded onto the reverse- 90

ly screw threaded portions a and b of the valve rod X and means are provided for rotating the valve rod X in one direction or the other in order to adjust the distance 100

between the slides G and H. The slides G and H, when being adjusted are prevented from turning owing to engagement of the webs c and d with the main valve rods T and U.

In this instance, a screw threaded portion e of the auxiliary valve rod X within the end of the arm W engages a screw f having a pointer g cooperating with a dial h which may be graduated to indicate pressures, and the auxiliary valve rod X may be 105 110

rectated by any suitable wrench or crank applied to the squared end *j*.

In the operation of the machine, the main valve member or main piston *F*, which in this instance is not shown to be adjustable, controls at its ends the opening and closing of the intake to the compressor cylinder through either one of the ports *k* and *o*, and also controls the closing of the discharge at the end of the stroke. Throughout the cycle, the closing of the discharge is not varied. The auxiliary valve member, constituted by the slides *G* and *H*, controls the opening point of the discharge, and these slides *G* and *H* are adjusted at the proper distance apart to vary the point of opening of the discharge for different ratios of compression. The main and auxiliary eccentrics *L* and *O* are set at such an angle and in proper relation with the crank pin *D* that the required timing of the main and auxiliary valve members is obtained.

In Figures 1 and 3, the compressor valve is shown in a position in which air is being admitted behind the piston *C*, through the port *k*, as the piston travels forward, while the slide *H* has opened the discharge through the port *o* from the opposite end of the cylinder. In Figure 4, all the parts are in the same position as that indicated in Figure 3, except that the auxiliary valve rod *X* has been rotated to adjust the slides *G* and *H* further apart so that the discharge will be opened later in the stroke, giving a suitable condition for higher discharge pressure.

In Figure 5 the piston *C* is at the beginning of its stroke and the main and auxiliary valve members are in neutral position, with both the intake and discharge shut off. In Figure 6 the piston *C* has started on its forward stroke, the intake is open through the port *k* and the discharge through the port *o* has been opened by the slide *H*. In Figure 7 the piston *C* has reached the end of its forward stroke and the main valve chamber or valve piston *F* has closed the discharge through the port *o*, and is about to open the port *o* to the intake.

In Figure 8 the port *o* is shown open to intake in front of the piston, and the slide *G*, now traveling in the reverse direction to that indicated in Figure 6, has opened the discharge behind the piston *C* through the port *k*. This cycle of operations will continue as the piston *C* reciprocates, the main valve member *F* continuing to control the opening and closing of the intake, and also the closing of the discharge at the end of the stroke, which is not varied. Likewise, the auxiliary valve member constituted by the slides *G* and *H* controls the opening point of discharge, which opening point may be adjusted for different ratios of compression.

I claim:

1. In a compressor, the combination with the cylinder and piston, of a mechanically operated combined inlet and discharge valve for the cylinder, comprising a main valve member controlling the closing of the discharge at the end of the piston stroke and having closed ends, which control the opening and closing of the intake, an auxiliary valve member carried by the main valve member and controlling the opening point of discharge from the cylinder, and means for adjusting said auxiliary valve member to vary the opening point of discharge.

2. In a compressor, the combination with the cylinder and piston, of a mechanically operated combined inlet and discharge valve for the cylinder, comprising a main valve member having closed ends controlling the opening and closing of the intake and an auxiliary valve member carried thereby, means for relatively adjusting said main and auxiliary valve members to vary the opening point of the discharge from the cylinder, and means for indicating the pressure in the cylinder, connected to the said adjusting means, whereby relative adjustment of the main and auxiliary valves may be accurately determined for different ratios of compression.

3. In a compressor, the combination with the cylinder and piston, of a mechanically operated combined inlet and discharge valve for the cylinder, comprising a main valve member and an auxiliary valve member operatively connected to an auxiliary valve rod carried thereby, means for relatively adjusting said main and auxiliary valve member to vary the opening point of the discharge from the cylinder, and means for indicating the pressures in the cylinder comprising a screw engaging a threaded portion of the auxiliary valve rod, a pointer connected to the screw, and a graduated dial cooperating with the pointer, whereby relative adjustment of the main and auxiliary valves may be accurately determined for different ratios of compression.

4. In a compressor, the combination with the cylinder and piston, of a mechanically operated combined inlet and discharge valve for the cylinder, comprising a main valve member having closed ends controlling the opening and closing of the intake, and the closing of the discharge at the end of the piston stroke, an auxiliary valve member carried by the main valve member and controlling the opening point of the discharge from the cylinder, and means for adjusting said auxiliary valve member to vary the said opening point of the discharge.

5. In a compressor, the combination with the cylinder and piston, of a mechanically operated combined inlet and discharge valve for the cylinder, comprising a main valve

member controlling the opening and closing of the intake at the ends thereof, and the closing of the discharge at the end of the piston stroke, an auxiliary valve member carried by the main valve member and controlling the opening point of discharge from the cylinder, means for adjusting said auxiliary valve member to vary the said opening point of the discharge, and means for in-

dicating the pressures in the compressor cylinder connected to the said adjusting means, whereby relative adjustment of the main and auxiliary valves may be determined for different ratios of compression. 10

In testimony whereof I have signed this specification.

FREDERICK W. PARSONS.
